(57) **CLAIM**

The ornamental design for a fly fishing station, as shown and described herein.

DESCRIPTION

FIG. 1 is a perspective view of the fly fishing station when in an open and accessible orientation for use or display; FIG. 2 is a front view in elevation of the fly fishing station as shown in FIG. 1;

FIG. 3 is a rear view in elevation of the fly fishing station as shown in FIG. 1;

FIG. 4 is a top plan view of the fly fishing station shown in FIG. 1;

FIG. 5 is a bottom view of the fly fishing station;

FIG. 6 is an end view in elevation of the fly fishing station as shown in FIG. 1; and,

FIG. 7 is the opposing end view in elevation of the fly fishing station that is shown in FIG. 6.

The broken line showing is included for the purpose of illustrating and forms no part of the claimed design.
